APPARATUS FOR PUMPING VOLATILE LIQUIDS

Leo I. Dana, Buffalo, N. Y., assignor to The Linde Air Products Company, New York, N. Y., a corporation of Ohio

Application June 15, 1940, Serial No. 340,672

7 Claims. (Cl. 103—153)

This invention relates to apparatus for pumping volatile liquids and particularly to plunger pumps adapted for pumping liquefied gases which have boiling point temperatures materially below 273° K. at atmospheric pressure, such as liquid oxygen, against relatively high heads of pressure, for example, against a head of pressure of from 1000 to 2000 lbs. per square inch gauge.

The invention has for its object generally the provision of an improved construction and arrangement of parts for pumps of the character indicated for achieving expeditiously both the exclusion of and convection away of heat from the liquid being pumped.

More specifically, the invention has for its object an improved construction for plunger pumps which are arranged for pumping highly volatile liquefied gases, such as liquid oxygen, and which employ counter-movement of liquid and plunger in order to avoid conveying heat through the plunger to the incoming liquid with special means, in the form of a thermal shield or jacket, associated with the discharge for absorbing heat in the liquid discharged and prevent its entering the pump where it may cause vapor binding or otherwise interfere with the desired operation of the pump.

Other objects of the invention will in part be obvious and will in part appear hereinafter.

The invention accordingly comprises the features of construction, combination of elements, and arrangement of parts, which will be exemplified in the construction hereinafter set forth, and the scope of the invention will be indicated in the claims.

For a fuller understanding of the nature and objects of the invention reference should be had to the following detailed description taken in connection with the accompanying drawing, in which:

The figure is a view, mainly in section, showing a plunger pump for pumping liquid oxygen, arranged in accordance with the invention.

Referring now to the drawing, a vertically arranged cylinder assembly is shown comprising a cylindrical element 10 formed with a pump chamber to receive liquid and having a relatively thick wall. The cylinder 10 is attached at the upper end to a second element 11 arranged to close one end of the pump chamber, and has a third element 12 superposed and attached and serving as a packing sleeve. The sleeve element 12 is preferably mounted at its top in a plate element 13 that may be a component of frame or casing that affords rigid support to the pump

assembly (the showing of such frame or casing being omitted from the drawing in the interests of clearness of illustration). The elements 10, 11, and 12, while they may be integral, are preferably separable, the attachment to one another being achieved in any convenient manner, for example, by threaded joints, as shown.

The cylinder assembly is completed by means of a block-like element 14 that is shown as 10 threadedly attached to the lower end of the cylinder 10. The block 14 thus closes the lower end of the pump chamber and forms a suitable head for the cylinder in which a plunger 15 is reciprocated.

The block 14 is preferably counterbored, as shown at 16, to provide a liquid receiving space and has a supply connection 17 that communicates with the receiving space 16 through a channel 18; the latter being bored in the block 14 and formed with an offset portion having a valve seat on which a valve element 19 seats. The valve element is arranged to open in response to the incoming stream of liquid and is therefore biased to closed position. Any convenient arrangement for this purpose may be employed, for example, a gravity seating arrangement, as shown. Access to the valve chamber in the block 14 is provided in any convenient manner, for example, by means of a removable plug 19'. The extent to which the block 14 is counterbored at 16 need only be such as to provide sufficient space beneath the plunger to collect solid bodies that may be in the liquid. The liquid therein also prevents the plunger from striking the lower 35 end of the pump chamber.

In order that liquid may be displaced from the pump chamber by the counter-movement of liquid and plunger, a clearance space in the pump cylinder 10 at the sides of the plunger is 40 also provided, whereby liquid may flow upwardly when the plunger moves downwardly. This latter clearance space is shown at 20 and leads to a displaced outlet connection 21, which communicates at the upper end with the clearance space 20 through a lateral bore in the element 11. Connection 21 leads to and communicates with another valve chamber in a housing element 22 that has a valve 23 seating therein. A discharge connection is provided at 24 which 45 communicates with the passage in the valve housing at a point beyond the valve seat. Access to the outlet valve chamber is provided through the removable plug 23'.

Here the element 11 is preferably counterbored 50 interiorly to a point considerably beyond the

threads which engage an end of a the element 10, and into this counterbored portion is fitted a bushing 25 of a material which both excludes heat and lubricates the plunger. The material preferred for this purpose is bonded graphite. The clearance of the bushing about the plunger is made relatively small and preferably not over .001 inch for plungers of the order of one inch in diameter. The lower end of the graphite bushing is preferably held in place by means of a spacing collar 26 which is of metal, clears the plunger, and is made to rest in a counterbored recess of slightly greater diameter than that employed for the bushing 25. The length of bushing 25 is at least equal to or greater than the stroke of the plunger.

The lower end of the graphite bushing is seen to be flush with the upper end of the enlarged portion of the deep cylindrical recess in block 11, the recess being preferably shaped or counterbored to receive the spacing collar 26 which is adapted to hold the bushing in place against any tendency to downward displacement. The collar 26 is also preferably bored through radially at a point communicating with the connection 21 in order to afford a suitable exit for the liquid displaced from the pump chamber. Between the collar 26 and the cylinder 10, a sealing washer 26' is also preferably inserted.

The sleeve 12, at its lower end, has a gland 12' adapted to engage the threaded nipple of element 11, while the upper end of the sleeve is closed by a gland or follower 27 that preferably has an exterior shoulder or collar adapted to be engaged by a nut 28, which is arranged to be in screw-threaded engagement with the exterior of the sleeve. The gland or follower is arranged to press down upon a plurality of packing rings 29, which are shown as filling the space in the packing sleeve between its inner wall and the plunger 15. These packing rings are preferably of a special construction and when liquid oxygen is being pumped are of a composition avoiding the use of a hydrocarbon or other substance that may react with the liquid oxygen. A preferred form of packing ring for such service comprises a washer-like body of suitable inert compressed material, such as shredded asbestos, incorporating an inert solid lubricant in comminuted form, for example, flake graphite, as disclosed in co-pending application, Serial No. 341,126, filed June 18, 1940, in the name of J. F. Patterson.

The plunger 15 is provided at its upper end with a transverse opening 30, or other suitable means, by which it may be mechanically coupled to suitable driving means, for example, by a pin to a walking beam (omitted from the drawing in the interests of clearness of illustration).

In order to provide a thermal shield for the pump chamber in accordance with the invention, which will absorb heat in the liquid discharged and operate to prevent heat from entering the pump in a manner which could cause so-called "vapor binding" on the suction stroke, the element 11 is provided with a cooling jacket comprising passage 31, which advantageously may have the form of a helical conduit having its lower end connected at 32 to the connection 24 and its upper end leading to a receiving device. The cooling passage preferably has an extension portion 33 connected to the outlet of the helical conduit and arranged to jacket a portion of the sleeve 12. An outlet connection for this portion is provided, as shown at 34. The arrangement shown permits the countercurrent circulation of

the liquid leaving the pump chamber in a passage which receives the liquid just discharged at its coldest end and provides for its exit at the warmer end so that a relatively uniform temperature gradient along the cooling passage is provided and contributes to the efficiency of the transfer of heat from the parts of the pump to the outgoing liquid which may be conveyed to a vaporizer or other desired receiving device.

10 In operation, it is seen that the pump employs the counter-movement of liquid and plunger in effecting the displacement of liquid from the pump chamber. Such displaced liquid is forced out through the connection 21, thence past the 15 valve 23 and through the conduit 24 into the passages 31-33 and thence discharged through the conduit 34. While the liquid is traversing the passages 31-33, it absorbs heat from the metal parts and from the packing sleeve 12. Such heat 20 cannot enter the liquid in the pump chamber and interference with pumping operation is avoided.

The method and arrangement of connections for operating the pump above described are disclosed and claimed in copending application, Serial No. 340,848, filed June 15, 1940 in the name of O. A. Hansen. Other features shown herein but not claimed are disclosed and claimed in copending application, Serial No. 340,849, filed June 15, 1940, in the name of O. A. Hansen.

30 Since certain changes may be made in the above construction and different embodiments of the invention could be made without departing from the scope thereof, it is intended that all matter contained in the above description or 35 shown in the accompanying drawing shall be interpreted as illustrative and not in a limiting sense.

Having described my invention, what I claim as new and desire to secure by Letters Patent is:

40 1. In apparatus for pumping a volatile liquid having a boiling point temperature materially below 273° K. at atmospheric pressure comprising the combination with a source of such liquid under a relatively low pressure, of a pump assembly comprising a cylinder formed with a pump chamber and having an inlet provided with a valve and connecting the suction end to said source, a plunger adapted to reciprocate in said cylinder and spaced from the inner wall thereof and providing thereby an appreciable clearance space therein, a discharge connection having a valve communicating with said clearance space, a closure for the other end of said pump chamber formed with an opening for passing said plunger 45 and having packing means associated therewith for sealing the passage of said plunger, and a thermal shield comprising a helical conduit connected to said discharge and having an outlet, said shield being associated with said closure and disposed concentrically about said pump assembly in the region of plunger entry into said pump chamber and arranged to be in heat conducting relation with the parts traversed by said plunger.

65 2. In apparatus for pumping a volatile liquid having a boiling point temperature materially below 273° K. at atmospheric pressure comprising the combination with a source of such liquid under a relatively low pressure, of a pump assembly comprising a cylinder formed with a pump chamber and having an inlet provided with a valve and connecting the suction end to said source, a plunger adapted to reciprocate in said cylinder and spaced from the inner wall thereof 70 and providing thereby an appreciable clearance 75 and

space therein, a discharge connection having a valve communicating with said clearance space at a point remote from said suction end, a closure for the other end of said pump chamber formed with an opening for passing said plunger and having packing means associated therewith for sealing the passage of said plunger, a guiding bushing for said plunger disposed in said closure on the pump chamber side, and a thermal shield comprising a helical conduit connected with said discharge and having an outlet, said shield being associated with said closure and disposed concentrically with said pump assembly in the region of plunger entry into said pump chamber and arranged to be in heat conducting relation with the metal parts traversed by said plunger.

3. In apparatus for pumping a volatile liquid having a boiling point temperature materially below 273° K. at atmospheric pressure comprising the combination with a source of such liquid under a relatively low pressure, of a pump assembly comprising a cylinder formed with a pump chamber and having an inlet provided with a valve and connecting the suction end to said source, a plunger adapted to reciprocate in said cylinder and spaced from the inner wall thereof and providing thereby an appreciable clearance space therein, a discharge connection having a valve communicating with said clearance space at a point remote from said suction end, a closure for the other end of said pump chamber formed with an opening for passing said plunger and having packing means associated therewith for sealing the passage of said plunger, a guiding bushing for said plunger disposed in said closure on the pump chamber side, and a thermal shield comprising a helical conduit connected with said discharge having successive portions, the first of which communicates with said discharge and is disposed in said closure and coiled about said guiding bushing, the second portion communicating with said first portion and being coiled about the upper portion of said closure adjacent packing disposed therein, said helical conduit being provided with an outlet completing said second portion.

4. In apparatus for pumping a volatile liquid having a boiling point temperature materially below 273° K. at atmospheric pressure comprising the combination with a source of such liquid under a relatively low pressure, of a pump assembly comprising a cylinder formed with a pump chamber and having an inlet provided with a valve and connecting the suction end to said source, a plunger adapted to reciprocate in said cylinder, a discharge connection having a valve communicating with said cylinder, a closure for the other end of said pump chamber formed with an opening for passing said plunger and having packing means associated therewith for sealing the passage of said plunger, a guiding bushing for said plunger disposed in said closure on the pump chamber side, and a thermal shield comprising a helical conduit connected with said discharge and having an outlet, said shield being associated with said closure and disposed concentrically with said pump assembly in the region of plunger entry into said pump chamber and arranged to be in heat conducting relation with the metal parts traversed by said plunger.

5. In apparatus for pumping a volatile liquid having a boiling point temperature materially below 273° K. at atmospheric pressure comprising the combination with a source of such liquid under a relatively low pressure, of a pump assembly comprising a cylinder formed with a pump chamber and having an inlet provided with a valve and connecting the suction end to said source, a plunger adapted to reciprocate in said cylinder, a discharge connection having a valve communicating with said cylinder, a closure for the other end of said pump chamber formed with an opening for passing said plunger, plunger packing and guiding means in said opening having associated therewith a solid lubricant substantially inert to oxygen, and a thermal shield comprising a helical conduit connected with said discharge and having an outlet, said shield being associated with said closure and disposed concentrically with said pump assembly in the region of plunger entry into said pump chamber and arranged to be in heat conducting relation with the metal parts traversed by said plunger.
6. In apparatus for pumping a volatile liquid having a boiling point temperature materially below 273° K. at atmospheric pressure comprising the combination with a source of such liquid under a relatively low pressure, of a pump assembly comprising a cylinder formed with a pump chamber and having an inlet provided with a valve and connecting the suction end to said source, a plunger adapted to reciprocate in said cylinder, a discharge connection having a valve communicating with said cylinder, a closure for the other end of said pump chamber formed with an opening for passing said plunger and having packing means associated therewith for sealing the passage of said plunger, and a thermal shield comprising a helical conduit connected with said discharge and having an outlet, said shield being associated with said closure and disposed concentrically with said pump assembly in the region of plunger entry into said pump chamber and arranged to be in heat conducting relation with the metal parts traversed by said plunger.

7. In apparatus for pumping a volatile liquid having a boiling point temperature materially below 273° K. at atmospheric pressure, comprising the combination with a source of such liquid under a relatively low pressure, of a pump assembly comprising a cylinder formed with a pump chamber and having an inlet provided with a valve and connecting the suction end to said source, a plunger adapted to reciprocate in said cylinder, a closure for the other end of said pump chamber formed with an opening for said plunger, plunger packing and guiding means in said opening having associated therewith a solid lubricant substantially inert to oxygen, and a thermal shield associated with said closure, comprising a liquid channel in communication with said discharge and having an outlet and disposed to envelop the region of plunger entry into said pump chamber and arranged to be in heat conducting association with said plunger and closure whereby the liquid discharged absorbs heat from the pump and plunger.
